US0D1070604S

(12) **United States Design Patent** (10) Patent No.: **US D1,070,604 S**
(45) Date of Patent: ** *Apr. 15, 2025

(54) **DISPENSER**(71) Applicant: **S. C. JOHNSON & SON, INC.**,
Racine, WI (US)(72) Inventor: **Brian T. Davis**, Burlington, WI (US)(73) Assignee: **S. C. JOHNSON & SON, INC.**,
Racine, WI (US)

(*) Notice: This patent is subject to a terminal disclaimer.

(**) Term: **15 Years**(21) Appl. No.: **29/906,364**(22) Filed: **Nov. 3, 2023****Related U.S. Application Data**

(63) Continuation of application No. 29/822,856, filed on Jan. 12, 2022, now Pat. No. Des. 1,018,306, which is a continuation of application No. 29/780,885, filed on Apr. 27, 2021, now Pat. No. Des. 944,087, which is a continuation of application No. 29/722,099, filed on Jan. 27, 2020, now Pat. No. Des. 920,801, which is a continuation-in-part of application No. 29/710,489, filed on Oct. 23, 2019, now Pat. No. Des. 920,804.

(57) **CLAIM**

The ornamental design for a dispenser, as shown and described.

DESCRIPTION

FIG. 1 is an isometric view of the top, front, and right side of the dispenser embodying my new design;

FIG. 2 is a front elevational view thereof;

FIG. 3 is a rear elevational view thereof;

FIG. 4 is a left side elevational view thereof;

FIG. 5 is a right side elevational view thereof; and,

FIG. 6 is a top plan view thereof.

The dash-dash-dash lines are included for the purpose of illustrating portions of the dispenser that form no part of the claimed design. The dash-dot-dash lines are included for the purpose of illustrating boundary lines that form no part of the claimed design.
